UNITED STATES PATENT OFFICE

RALPH G. NEWSOME, OF NEWPORT NEWS, VIRGINIA

GRADING LEVEL

Application filed June 22, 1928. Serial No. 287,488.

This invention relates to grading levels, and the primary object of the present invention is to provide an improved level of this kind by means of which a level line between 5 different points or any rise or fall between spaced points may be readily and accurately obtained.

A further object is to provide a single instrument or unit capable of selective use with 10 speed and accuracy for obtaining a desired percent of fall or rise between spaced points, to determine the percent of existing rise or fall between spaced points, or to obtain a level line between distant points.

15 Still another object is to provide novel means for furnishing the ends of the bubble tube holder of the level with sight pieces, whereby when a horizontal or inclined line is attained, such line can be extended indefinitely.

20 Other objects and advantages will become apparent as the nature of the invention is better understood, and the same consists in the novel form, combination and arrangement of parts hereinafter more fully described, shown in the accompanying drawings and claimed.

In the drawings:

Figure 1 is a fragmentary side elevational 30 view of a grading level embodying the present invention, partly broken away and in section.

Figure 2 is a top plan view of the construction shown in Figure 1.

35 Figure 3 is a transverse vertical section on line 3—3 of Figure 1.

Figure 4 is a similar view on line 4—4 of Figure 1.

40 Figure 5 is an enlarged perspective view of one of the sight pieces; and

Figure 6 is a view of the level drawn on a 45 smaller scale and showing the spirit level proper adjusted at an angle to the stock or straight edge as practiced in certain uses of the level.

Referring more in detail to the drawings, the present grading level embodies a spirit level proper consisting of an elongated metallic holder 5 in which is suitably mounted 50 an elongated transparent bubble tube 6 hav-

ing a series of transverse graduations thereon as generally indicated at 7. As shown, the holder 5 consists of a hollow body having an elongated slot 8 in the top thereof through which the bubble tube 6 is exposed, and provided with solid rectangular end portions 9, the bubble tube 6 being firmly retained in the upper portion of the hollow body of the holder 5 by means of closure plates 10 applied and suitably fastened to the open under side 60 of said body of the holder at opposite sides of the longitudinal center of the latter. As shown, a yieldable cushion 11 may be interposed between each end of the bubble tube 6 and the adjacent closure plate 10, whereby 65 said bubble tube is firmly but yieldably held in place. The top wall of the body of the holder 5 is preferably of longitudinally arched or upwardly curved form, while the bubble tube 6 is of similar arcuate form, the curvature and the arrangement of the graduations 7 being such that the percentage of elevation 70 can be determined by the position of the bubble with respect to said graduations.

The level further embodies an elongated 75 base plate or bar 12 arranged with its longitudinal axis parallel with the longitudinal axis of the holder 5 and tube 6, and provided intermediate its ends with a pair of spaced upstanding ears 13 between which the bubble 80 tube holder 5 is suitably pivoted as at 14 upon a transverse horizontal axis and intermediate its ends for longitudinal swinging or tilting adjustment relative to the base bar or plate 12. Upright adjusting screws 15 are 85 adjustably threaded through the opposite solid end portion 9 of the holder 5, and these adjusting screws are adapted to bear at their lower ends upon the upper surface of the base bar 12 at opposite sides of the pivot 90 14. It is thus apparent that by relatively adjusting the screws 15 in opposite directions, the spirit level proper may be accurately 95 tiltably adjusted in any desired angular relation to the base bar 12 without any danger of accidental loss of such adjustment. The holder and base bar are preferably made of light metal, and it is thus apparent that the construction described will be extremely simple and durable as well as light in weight. 100

The base bar 12 has a flat bottom surface and is longer than the holder 5 so as to project at its ends beyond the ends of the latter. These projecting ends of the base bar 12 are 5 provided with suitable openings to receive screws 16 or other like fastening elements, whereby the base bar 12 may be firmly, flatly secured on the top of a suitable stock or straight edge 18.

- 10 In accordance with the present invention, the bubble tube holder 5 is also provided with end sight pieces, the front sight piece being indicated at 19 and the rear sight piece being indicated at 20. Except for the character of 15 the sighting means, these two sight pieces are similar in construction, consisting in general of a flat vertically elongated plate provided at its lower end with a pair of spaced transverse horizontal flanges 21 disposed one above 20 the other, and provided in its lower end with an opening 22 between the flanges 21. In practice, the sight pieces are secured at their lower ends against the opposite ends of the bubble tube holder 5 by means of stud screws 25 23 passing through the openings 22 and threaded into sockets provided in the ends of the end portions 9 of the bubble tube holder 5 as clearly shown in Figure 1, the flanges 21 respectively engaging the upper and lower 30 surfaces of the end portions 9 to maintain the sight pieces vertically disposed or against turning relative to the holder 5 about the screws 23. In this way the sight pieces are readily and firmly attached although of extremely simple and durable construction. As 35 illustrated, the front sight piece 19 is provided in its upper end portion with an aperture of relatively small size forming a peep hole 24, and the rear sight piece has a vertically elongated slot in its upper end portion as at 25, said slot being laterally enlarged near its upper end as at 26 and having a horizontal or transverse sighting wire 27 mounted in this enlarged portion of the slot. 40
- 45 In setting the level for use, it is placed on the two points to be levelled and the position of the bubble in the tube 6 is noted, after which the level is reversed end for end and the position of the bubble again noted. By 50 means of the thumb screws 15, the bubble is then brought to exactly half way between the two marks or graduations at which the bubble was thus noted, whereupon the level is ready for use with the bubble tube exactly 55 level with the bottom of the stock or straight edge 18. It will of course be understood that the thumb screws 15 are adjusted to tilt the spirit level proper relative to the straight edge or stock 18 for setting the level as above 60 described, and for accuracy, the above operation can be repeated.
- 65 After the level has been set for use in this manner, and it is desired to obtain any rise or fall, the percent of which can be regulated by the length of the straight edge 18 and the

height one end of the level is raised or lowered, such end of the level or the stock 18 is lowered or raised the desired amount, and then the bubble is centered again in the tube 6 by adjusting the screws 15. For example: 70 if a fall of one inch per foot is desired, a stock ten feet long is used and one end thereof is lowered ten inches. The bubble is then centered in the tube 6 by adjustment of the screws 15, and the straight edge will be adjusted with respect to the spirit level proper to correspond with an inclination of one inch to one foot. 75

To obtain a level line to a distant point, as from one corner of a building to another, the level is placed on the point to be leveled from, with the sight pieces attached and with the front or peep sight piece 19 farthest from the point to be leveled. The sight pieces are then used to sight from the point to be leveled from to the point to be leveled, allowance being made for the height of the sights above the base of the level. Naturally, in this use of the instrument, the spirit level proper is set in level condition as first above described. 80

Should it be desired to obtain a distant point on an incline or on a grade, the percent of rise or fall is obtained as explained above. The ends of the stock or straight edge are then fixed to maintain said stock or straight edge at the proper inclination and the spirit level proper and its base are detached from the stock or straight edge and the spirit level proper is set in a level condition with respect to the base bar 12 as first described above. The spirit level proper is then again attached to the stock or straight edge by fastening the base bar 12 thereon, after which the distant point can be obtained by sighting through the sight pieces. 90

In view of the above it will be seen that I have provided a very simple and efficient single unit or instrument by means of which the several desired operations may be carried out with speed and accuracy. 95

Minor changes may be made without departing from the spirit and scope of the invention as claimed. 100

What I claim as new is:

1. In a grading level, the combination with a straight edge, of a base bar secured upon said straight edge and having upstanding ears intermediate its ends, a spirit level proper including a bubble tube holder pivoted intermediate its ends between said ears and upon a transverse horizontal axis for longitudinal tilting adjustment, adjusting screws threaded through the ends of said bubble tube holder and bearing upon said base bar for use in tiltably adjusting said bubble tube holder, said bubble tube holder comprising an elongated hollow body portion having an arcuate top wall provided with a longitudinal slot, and an elongated arcuate bubble tube mounted on said wall of the holder and provided with 115 120 125 130

a series of transverse graduations from end to end exposed through said slot.

2. In a grading level, an elongated bubble tube holder, sight pieces detachably fitted over and secured against the ends of said bubble tube holder, said sight pieces comprising vertically elongated plates provided at their upper ends with sighting means and formed with spaced horizontal flanges at their lower ends arranged to flatly engage the top and bottom surfaces of the ends of said holder, and horizontal screws passing through the lower ends of the sight pieces and threaded into the ends of said holder to removably secure said sight pieces in place said bubble tube holder comprising an elongated hollow portion having an arcuate top wall provided with a longitudinal slot, and an elongated arcuate bubble tube mounted on said wall of the holder and provided with a series of transverse graduations from end to end exposed through said slot.

In testimony whereof I affix my signature:
RALPH G. NEWSOME.
